Specification for Design.

Patented Dec. 14, 1920.

Application filed June 18, 1920. Serial No. 390,045. Term of patent 7 years.

To all whom it may concern:

Be it known that we, JOHN SHALHOUB and LOUIS H. ESSELMANN, the said JOHN SHALHOUB being a Syrian, a subject of the Sultan of Turkey, and a resident of the city of St. Louis, State of Missouri, and the said LOUIS H. ESSELMANN, being a citizen of the United States, and a resident of the city of St. Louis, State of Missouri, have invented a new, original, and ornamental Design for a Pastry Cone, of which the following is a specification, reference being had therein to the accompanying drawings, forming part thereof.

Figure 1 is a perspective view of a pastry cone showing our new design; and

Fig. 2 is a sectional view of the same on the line 2—2 in Fig. 1.

We claim:

The ornamental design for a pastry cone as shown.

In testimony whereof, we hereunto affix our signatures.

JOHN SHALHOUB.
LOUIS H. ESSELMANN.
